HERMETICALLY SEALED SUBMERSIBLE
PUMPING STRUCTURE

Frederick C. Gilman, Pompton Lakes, N. J., assignor to Worthington Pump and Machinery Corporation, Harrison, N. J., a corporation of Delaware

Application March 1, 1945, Serial No. 580,469

7 Claims. (Cl. 103—87)

1

This invention relates to motion transmitting devices, and more particularly to moisture exclusion means therefor.

An object of the present invention is to provide novel means for effectively transmitting rotary motion through a moisture-proof barrier.

Another object is to provide in a rotative power transmitting member comprising two sections, an operating connection between the two sections for transmitting rotary motion from one section to the other, wherein a fluid-tight seal or barrier is connected with the operating connection in such manner as to completely and hermetically seal one section of the power transmitting member from the other section thereof.

Another object of the present invention is to provide a deep well pump wherein an electric motor or other type of driver is completely submerged under normal operating conditions, and in which novel means are incorporated for completely and hermetically sealing the electric motor or other driver from contact with the liquid within which the unit is submerged.

Another object is to provide in a pump, a casing wherein the motor is mounted in the lower end of the casing for driving a pump operating shaft located above the motor, in which the motor is provided with a drive crank having an operating connection with a driven crank fixedly related to the pump shaft, and in which novel means are sealingly connected with the operating connection and the pump casing to completely and hermetically seal the motor from the pump structure located thereabove.

A further object is to provide in a deep well pump, a drive crank, a driven crank, and a nutating operating connection between the drive and driven cranks, in which a novel deformable fluid-tight barrier is sealingly connected with the nutating operating connection and the pump casing to completely and hermetically seal a drive crank from the driven crank.

A still further object is to provide a deep well pump wherein the motor is incorporated in the casing beneath the pumping unit for complete submergence in the fluid being pumped, in which a deformable seal is incorporated in the casing to provide a fluid-tight partition therein which isolates the motor from the pumping unit, and in which means are provided for maintaining air pressure inside the motor at the same value as the effective fluid pressure on the outer side of the partition.

With these and other objects in view, as may appear from the accompanying specification,

2

the invention consists of various features of construction and combination of parts, which will be first described in connection with the accompanying drawings, showing a hermetically sealed submersible pumping structure of a preferred form embodying the invention, and the features forming the invention will be specifically pointed out in the claims.

In the drawings:

10 Figure 1 is a longitudinal sectional view of a portion of a pump casing showing a centrifugal pump housed therein and incorporating the invention.

15 Figure 2 is a cross sectional view taken along the line 2—2 of Figure 3.

20 Figure 3 is an enlarged sectional view illustrating the operating connection between the drive and driven cranks and the deformable seal which completely and hermetically divides the power-containing section of the pump structure from the remaining pump structure located thereabove.

25 Figure 4 is a view similar to Figure 3 but illustrating a different type of deformable seal.

30 Figure 5 is a view similar to Figure 3 but illustrating another form of construction.

35 In the drawings, Figures 1, 2, and 3, illustrate a pump casing 1 which is made up of sections 2, 3, 4, and 5 arranged end to end and connected into a unitary structure in any suitable manner, as by threaded joints. The section 2 contains the stationary pump passage structures 6 and pump rotor 7, the latter including a rotative shaft 8 and fluid impellers 9 fixedly connected therewith. Fluid inlet openings 10 are provided in the section 2 for admitting fluid to be pumped to the inlet eye 11 of the rotor 7.

40 In Figures 1 and 3, the lower end of the section 2 is provided with a transverse end wall 11 which is provided with a bearing 12 for rotatably supporting the lower end of the rotor shaft 8, and this wall is threadedly connected at 13 with the section 3.

45 Beneath the wall 11 and inside the lower end of the pump casing 1 is mounted an electric motor 14, the latter including a drive shaft 15 which is arranged in co-axial relationship with the rotor shaft 8. To the upper end of the shaft 15 is fixedly connected a rotative member or drive crank 16. A rotative member or driven crank 17 is fixedly connected with the rotor shaft 8. Rotary motion is transmitted from the drive crank 16 to the driven crank 17 through a nutational operating connection 18, the latter comprising a shaft-like member with its axis

inclined to the common axis of the drive shaft 15 and the rotor shaft 8.

Self-aligning bearings 19 are provided for the ends of the operating connection 18, which bearings are respectively incorporated in the drive crank 16 and the driven crank 17. In the arrangement shown, the operating connection 18 operates with a nutational movement about a point located on a line common to the axes of the drive shaft 16 and the rotor shaft 8.

Both the driving crank 16 and the driven crank 17 are designed as near as possible as bodies of revolution in order to obtain a balanced rotor for the pump as well as the motor and a minimum of fluid friction for the driven crank 17 which is submerged in water or other fluid being pumped. A bearing 20 is incorporated in the section 4 to afford support for that end of the motor shaft 15 which is connected with the drive crank 16. While the bearings or bushings 19 are eccentric with respect to the shafts 8 and 15, the bearings are inclined in such a manner as to have a common axis for their bores which receive the ends of the operating connection 18.

A spherical bearing surface 21 is provided on the connection 18 near its center, which surface is guided in a stationary spherical bearing 22 consisting of two co-acting bearing sections 23 and 24. The section 23 is fixedly related to the section 24 by bolts 25. The bolts 25 pass through the wall part 26 of the section 24, this wall part including an annular flange 27 which is clamped between the adjacent ends of the sections 3 and 4. The wall 26 is threadedly connected at 28 and 29 with the sections 3 and 4, respectively, to connect the parts into a unitary structure.

On the outer or pump side of the spherical bearing 22 is arranged a bell-shaped flange structure 30 which is mounted on the connection 18. The flange structure 30 consists of flanges 31 and 32, the former having a pressed fit 33 with the member 18 and is held in place by a nut 34 threadedly connected at 35 with the member 18. Bolts 36 fixedly connect the section 32 with the section 31.

At its outer rim, the flange structure 30 supports a flexible diaphragm 36, the latter having a beaded edge 37 which is rigidly clamped between the sections 31 and 32 in a plane at right angles to the longitudinal axis of the member 18. The outer rim of the diaphragm 36 is clamped to the wall 26 by an annular ring 37 which is clamped to the wall 26 by bolts 38. While the wall 26 constitutes a part of the spherical bearing structure 22, this wall constitutes also a casing cover of the motor 14.

The inner rim of the diaphragm 36 performs with the nutational operating connection 18 and the flange sections 31 and 32 a periodical spherical motion so that the diaphragm 36 is thereby deformed between the two extremes shown on opposite sides in Figure 3, that is, maximum deformation in one direction on one side of the operating connection 18 and maximum deformation in the opposite direction on the diametrically opposite side of the operating connection.

In order to minimize the dynamic force which the diaphragm must overcome in displacing the water in accordance with its own deformation, the driven crank 17 carries a surface 39 adjacent to the diaphragm 36, which surface is seen not to be a surface of revolution but a surface following the local shape of the deformed dia-

phragm 36. This is possible because the deformation of the diaphragm travels around the axis of the whole unit at the same rate as the pump rotor and motor shaft, and thereby at the same rate as the driven crank 17. The relative motion between the surface 39 and the flexible diaphragm 36 is therefore merely a slip of shear motion across the narrow body of water between these two parts, because the surface 39 revolves with the rotor shaft 8 while the flexible diaphragm 36 does not. The distance between the surface 39 and the diaphragm 36, however, remains essentially constant, thereby shielding the diaphragm 36 from the dynamic forces of the water.

It will be noted that the bearing and casting cover defined by the wall part 26 in connection with the diaphragm 36, the flange structure 30, and the nutational operating connection 18 form an uninterrupted and moisture-proof barrier or wall between the inside of the motor and the well and pump which are filled with water, since the outer and inner margins of the flexible diaphragm 36 are hermetically sealed or fixed to the attached parts 26 and 31 and 32, respectively.

Since the forces on the rapidly deformed diaphragm 36 obviously should be kept as low as possible in order to increase the life of the diaphragm, Figure 1 illustrates means which assure equal pressure at all times on the two sides of the flexible diaphragm; that is, equal pressure at the inside and outside of the motor 14. The essential element of this feature comprises a flexible and impervious bag 40 which is protected against mechanical injury by a coarse screen 41 attached to the section 5. In assembly, the bag 40 is permitted to rest loosely against the screen 41 in a collapsed position. As fluid pressure on the outside of the motor increases as the unit is lowered into the well or as a consequence of variations in the water level, the bag 40 expands to a position as shown in Figure 1, thereby compressing the air inside the motor. Different equilibrium of pressure will be maintained by corresponding deformation of the bag 40 if the air inside the motor expands or contracts due to changes in temperature. In order to minimize the necessary deformation of the bag 40, it is desirable to keep the volume of air inside the motor 14 reasonably small. The filler piece 42 attached to the crank 16 shows an example of how unnecessary air spaces may be eliminated.

In connection with deep well turbine pumps, it is of great advantage to place the driving motor in the immediate vicinity of the pump near the bottom of the well. This arrangement avoids the conventional long shaft between the motor above the ground and the pump below the ground water level. The arrangement of the motor near the pump makes it necessary to seal the motor hermetically and permanently from the outside because the usual variations of the water level in the well require the motor to be completely submerged. Attempts to operate a motor with its inner rotating parts exposed to water have not been successful.

The usual method of sealing a rotating machine against a fluid involves a sealing device intended to prevent the fluid from passing between the stationary housing of the machine and the rotating shaft at the point where the latter passes from the inside to the outside of the machine. Such methods have not been successful. The

present invention avoids the necessity of sealing a rotating shaft by transmitting power from the inside to the outside of the casing through an intermediate operating connection which performs a nutational motion without rotation about its own axis. By this arrangement it becomes possible to establish a seal between the stationary housing and the nutational operating connection by means of a flexible diaphragm or similar element which is operatively fastened to the stationary housing as well as the nutational operating connection, following the motion of the latter entirely by its deformation.

The diaphragm 36 may comprise rubber or synthetic materials of like properties with or without reinforcement, depending upon the purpose for which the machine is to be used. If the materials which are available for making the flexible diaphragm 36 should be undesirable for some applications of the sealing device, it is possible to replace the diaphragm by an arrangement of bellows in the manner shown in Figure 4, which bellows may comprise metal or any other suitable material. In this form, it will be seen that the essential characteristics of the design previously described are maintained in practically all respects, although the sections 43 and 44, which correspond to the sections 23 and 24, respectively, are of slightly greater vertical dimension than the sections 23 and 24. The bellows units 45 and 46 are connected one with the other in end to end relationship, and one end of the unit 45 is connected with the annular ring 47 and one end of the unit 46 is connected with a flange 48 attached to the nutational operating connection 49, the latter corresponding to the operating connection 18. The flange 48 is hermetically fixed or sealed to the operating connection 49 in a plane at right angles to the longitudinal axis of the operating connection.

An alternate form of construction is shown in Figure 5, wherein the spherical bearing structure 22 of Figures 1 and 3 is replaced by a bearing 50 mounted in the motor driven crank 51, which has been suitably extended vertically. The crank 51 also carries a bushing or bearing 52 corresponding to one of the bearings 19, and the other end of the nutational operating connection 53 is supported in a bushing or bearing 54 incorporated in the driven crank 55 and corresponding to the other of the bearings 19. By the arrangement of Figure 5, the attachment of the flexible diaphragm 56 to the operating connection 53 is brought considerably closer to the center about which the shaft or operating connection oscillates, whereby the rapid periodical deformations of the diaphragm are appreciably reduced, which feature can be expected to prolong the life of the diaphragm and to permit the use of materials which could not be employed in connection with a diaphragm construction and arrangement such as that shown in Figures 1 and 3.

In the structure of Figure 5, the operating connection 53 includes an annular shoulder 57 located adjacent the bearing 50 and against which is pressed a washer-like flange 58. The beaded rim 59 of the diaphragm 56 is clamped between the flange 58 and a similar flange 60, the latter having a sleeve 61 which is pressed on the operating connection 53, as by a nut 62. Thus the diaphragm 56 is hermetically sealed or fixed to the operating connection 53 in a plane at right angles to the longitudinal axis of the operating connection. The outer rim 63 of the diaphragm is clamped between an annular member 64 at-

tached to the casing structure 65 and a clamp ring 66, as by bolts 67. This form of the invention, as well as that shown in Figure 4, includes a driven crank so designed as to minimize the relative motion between the crank and the deformable diaphragm or bellows in the same manner as the structure shown in Figures 1 and 3.

Circuit wires or cables for the electric motor may be protected in a fluid-tight conduit extending downwardly along the outer surface of the pump casing as indicated generally at 68 in Figure 5, a portion of the motor being indicated generally at 69.

In the form shown in Figure 5, the drive crank 51 includes a shaft part 70 which is supported in a bearing 71, which shaft part is bolted at 72 to a sleeve member 73, the latter being bolted at 74 to the end of the rotor 75 of the motor 69.

While the invention has been illustrated and described in connection with a deep well pump, the invention is equally well adapted to other fields of service wherein pumps and other rotating devices may be powered by an electric motor or other type of driver which must be sealed completely and hermetically against the surrounding fluid. In fact, the invention may be used in any situation where it is desired to transmit rotative motion through a hermetically sealed wall or barrier. Important fields of application, for example, reside in pumps and machinery for handling poisonous fluids, including petroleum, where it is frequently necessary to pump fluids which cannot be permitted to communicate in the least with the atmosphere.

The term "nutational" as used herein embraces a motion wherein the endwise halves or portions of the shaft-like operating connections 18, 49, and 53 travel in conical paths the bases of which are of unvarying diameters, except as to any variation which may be caused by working tolerances or wear or both, and in which the conical paths have a common vertex, the latter constituting the point about which the nutational motion of the shaft-like members or operating connections takes place.

It will be understood that the invention is not to be limited to the specific construction or arrangement of parts shown, but that they may be widely modified within the invention defined by the claims.

What is claimed is:

1. In a submersible pumping structure, a housing, a rotative drive crank in said housing, a rotative driven crank in said housing, a fluid-tight wall between said drive crank and said driven crank and having a deformable portion, said fluid tight wall being connected in fluid tight relationship to said housing, and a nutating operating connection between said drive crank and said driven crank for transmitting rotary motion from the drive crank to the driven crank, said operating connection extending through said deformable portion and being fixedly connected therewith to provide a fluid-tight joint between the deformable portion and said operating connection, said drive crank and driven crank being positioned to rotate about a common axis, said nutating operating connection comprising a shaft-like member arranged with its longitudinal axis at an angle to said common axis, said deformable portion being fixed to said shaft-like member in a plane at right angles to the longitudinal axis of the shaft-like member, said driven crank having a bell-like contour conforming to the contour

of said deformable portion and being spaced slightly therefrom.

2. In a device of the type described, a pump casing having a flexible fluid-tight end, a motor located in said casing adjacent said fluid-tight end and having a first crank, a pump unit located in said casing and having a rotor provided with a second crank, a nutating operating connection between the first crank and the second crank, and a deformable means connected with said nutating operating connection and the casing to provide a fluid-tight partition between the pump unit and the motor, said casing having a fluid inlet located between said deformable means and said pump unit elastic fluid in said casing between said flexible fluid tight end and said deformable means, said fluid-tight end being flexible to respond to fluid pressure effective on the exterior side thereof for compressing said elastic fluid to cause an effective pressure on the motor side of said deformable means equal to the fluid pressure effective on the pump unit side of the deformable means.

3. In a submersible pumping means structure having a housing with power means and pumping and means operatively connecting said power means and pumping means and a flexible diaphragm connected in fluid tight relationship to said housing and to said connecting means for hermetically sealing said power means from said pumping means, a crank member attached to said pumping means having an internal coniform surface spaced slightly from one surface of said diaphragm whereby the diaphragm is shielded from the dynamic effects of the fluid being pumped.

4. In a submersible pumping structure for submergence in a fluid to be pumped, a housing having a pumping chamber and a motor chamber, pumping means in said pumping chamber, motor means in said motor chamber, means operatively connecting said motor means to said pumping means, flexible means operatively connected in fluid tight relationship to said housing and to said connecting means for hermetically sealing said chambers one from the other, said flexible means being acted upon on one side by the pressure of the fluid being pumped in said pumping chamber and on the other side by the pressure of the fluid in said motor chamber, elastic fluid in said motor chamber, and means for equalizing the pressures of the elastic fluid and the fluid being pumped comprising flexible means acted upon by each of said fluids connected to that part of said housing which forms said motor chamber.

5. In a pumping structure for submergence in a fluid to be pumped, a housing having a pumping chamber and a motor chamber, pumping means in said pumping chamber, motor means in said motor chamber, means operatively connecting said pumping means to said motor means,

elastic fluid in said motor chamber, flexible means connected in fluid tight relationship to said connecting means and to said housing and separating said pumping chamber from said motor chamber, and means for maintaining the pressure of said elastic fluid substantially equal to that of the fluid being pumped whereby the fluid pressures on each side of said flexible means are substantially equalized comprising a flexible partition in said housing separating said motor chamber from the exterior of the housing.

6. In a pumping structure for submergence in a fluid to be pumped, a housing having a pumping chamber and a motor chamber, pumping means in said pumping chamber, motor means in said motor chamber, means operatively connecting said pumping means to said motor means, elastic fluid in said motor chamber, flexible means connected in fluid tight relationship to said connecting means and to said housing and separating said pumping chamber from said motor chamber, and means for maintaining the pressure of said elastic fluid substantially equal to that of the fluid being pumped whereby the fluid pressures on each side of said flexible means are substantially equalized consisting of a flexible partition in said housing separating said motor chamber from the exterior of the housing.

7. In a submersible pumping structure having a housing with its exterior in contact with the fluid to be pumped, a motor chamber in said housing, a pumping chamber in said housing, motor means in said motor chamber, and pumping means in said pumping chamber, and connecting means operatively connecting said motor means to said pumping means, the combination of a flexible partition connected in fluid tight relationship to said housing and to said connecting means and hermetically sealing said motor chamber from said pumping chamber, elastic fluid in said motor chamber, and a flexible partition communicating with the interior of said motor chamber and with the exterior of said housing connected in fluid tight relationship to said housing.
